MACHINE FOR FORMING SHAPES

Carl M. Yoder, Lakewood, Ohio

Application August 23, 1939, Serial No. 291,549

5 Claims. (Cl. 153—54)

This invention relates to a machine for forming a hollow body from sheet metal stock, and more particularly to the mounting of the shaping elements. The invention is particularly applicable to a machine for shaping sheet metal into tubular form, the final set of shaping or sizing rolls being arranged to operate thereon prior or subsequent to the welding of the form edges where such operation is to be employed.

10 The machine herein shown for illustrative purposes operates continuously to shape stock fed from a coil into tubular form with its side edges in opposed relation ready for welding, and such machine may be associated with a cutting off mechanism wherein the stock is severed into sections.

In all machines for forming sheet metal into tubular form, of which I have knowledge, difficulty has been experienced in overcoming displacement of the rolls, or certain thereof, on their shafts, especially in the employment of stock of heavy gauge. It is necessary that the set of rolls which provide the final forming steps in such a machine should be rigidly secured in position, so that each roll rotates in a plane at right angles to its shaft and maintains its alignment with the opposed or related roll. This condition applies particularly to that set of rolls which is utilized for sizing the formed stock. It has been found, where the roll fails to accurately fit the shaft, that is, its bore is larger from end to end than the shaft or one end of the bore is larger than its other end, that the roll becomes displaced or out of alignment and hence sets up a wobbling movement or rotates in a plane other than at right angles to the shaft axis. This abnormal condition has been found to occur where the diameter of the bore of the roll or that portion of the shaft on which the roll is mounted, differs one or two thousandths of an inch or more, one from the other. In forming piping great accuracy as to the external diameter thereof is required, so that the sizing rolls must effect sizing to micrometer dimensions in many instances and the piping must be of uniform size throughout its length.

One object of the invention is to provide an improved mounting for a roll capable of eliminating the conditions above referred to.

50 Another object of the invention is to provide an improved mounting for rigidly securing a roll to a shaft and permitting ready assembly and disassembly.

Another object of the invention is to provide an improved mounting for a roll wherein a wedg-

ing action is employed to secure the roll to its shaft.

Other objects of the invention will be apparent to those skilled in the art to which my invention relates from the following description taken in connection with the accompanying drawing, wherein.

Fig. 1 is a side elevation of a portion of a machine, embodying my invention, adapted to shape sheet metal into hollow form.

Fig. 2 is a plan view of the line 2—2 of Fig. 1.

Fig. 3 is an elevation looking towards the right of Fig. 1, partly in section on the line 3—3 of Figs. 1 and 2.

Fig. 4 is a fragmentary section through a sizing roll and its mounting.

Fig. 5 is a detail view.

Fig. 6 is a view on the line 6—6 of Fig. 5.

In the drawing, 1 indicates as an entirety a machine for operating on sheet metal of any desired thickness as it comes from the mill, either hot or cold rolled, the metal being supplied in any desired manner, as from a coil, and fed to roll passes, whereby the metal stock is continuously shaped into hollow form, following which the related edges of the form may be welded and/or prior to or after welding the form may be cut in sections. As such machines are well known, I have shown only the last three roll passes 1a, of such a machine adapted to form piping A and a pair of sizing rolls 2, 2a, mounted on shafts 3.

For illustrative purposes my improved mounting is shown applied to only one of the sets of forming rolls, namely, the final set, which may be utilized to size the stock. The shafts 3 are mounted in suitable anti-friction bearings in housings 4, 4a, and at one end the shafts 3 are provided with gears 5, 5, in meshing relation, whereby one shaft is driven by the other shaft; for this latter purpose the lower shaft 3 is extended and provided with a worm gear 6 in mesh with a worm 7 fixed to a shaft 8, which is driven by a motor (not shown). The housing 4a is preferably shaped to form a casing for the gearing. The shafts for the rolls of each pass 1a may be mounted and drivingly connected to the shaft 8 similarly to the mounting and drive means above described for the shafts 3, 3.

Each roll 2, 2a, is mounted on and fixed to its supporting shaft 3 in the following manner: 9 indicates a sleeve bored to slidably and snugly fit the shaft 3. The sleeve consists of a body portion 9a and a plurality of extensions 9b integral with and extending from one end of the body portion in circumferential relation to the shaft 3. The

inner surfaces of the extensions $9b$ are sized to fit and engage the shaft, whereas the outer surfaces are curvilinear and tapered toward their free ends and cooperate to define a cone-like seat 5 on which the sizing roll is mounted, the roll being conically bored to complementary fit the extensions $9b$ and so mounted thereon that its outer side projects beyond the free ends of the extensions. The shaft 3 is provided on one end portion 10 tion, that is, that end portion adjacent the extensions $9b$, with a fixed collar or abutment $3a$ (preferably formed integrally therewith) and one or more spacers 10 (only one being shown) are interposed between the collar $3a$ and the adjacent 15 side of the sizing roll to form an abutment means therefor, and to align the rolls one with the other. The opposite end portion of the shaft 3 is provided with screw threads $3b$ to take a nut 11 , which is arranged to be tightened against the adjacent end of the sleeve 9 , such operation serving 20 to force the extensions $9b$ axially of the shaft and sizing roll, which being held stationary by the collar $3a$, compresses the extensions $9b$ inwardly into rigid relation to the shaft, so that the extensions form a circumferential wedge between 25 the shaft and roll. As the metal of the sleeve 9 is slightly resilient and the extensions $9b$ are spaced from each other, they may be compressed inwardly to effect a wedging action as above set 30 forth, so that when the nut 11 is tightened, the sizing roll is fixedly secured from end to end to the shaft and danger of its wobbling or getting out of alignment with the axis of the shaft is eliminated.

35 The nut 11 may be fixed in tightened position by a jam nut 12 .

If desired the sleeve 9 may be keyed to the shaft 3 and when necessary one or more spacers may be provided between the nut 11 and the adjacent 40 end of the sleeve.

To those skilled in the art to which my invention relates, many changes in construction and widely differing embodiments and applications of the invention will suggest themselves without departing from the spirit and scope of my invention. The disclosures and the description herein are purely illustrative and are not intended to be in any sense limiting.

What I claim is:

1. In a machine of the class described, the combination with a pair of housings, of upper and lower shafts mounted therein, a roll mounted on one of said shafts, a sleeve slidably fitting the other shaft and provided at one end with spaced 55 extensions the outer surfaces of which define a cone-like seat, abutment means fixedly secured to said shaft, a roll aligned with said first mentioned roll and having a conical bore fitting said seat, and engaging said abutment means, and 60 means on said shaft arranged to engage the other end of the sleeve and force it endwise to effect a wedging action of said extensions between said shaft and said roll, whereby the latter is rigidly connected to said shaft.
- 65 2. In a machine of the class described, the combination with a pair of housings, of upper and lower shafts mounted therein, a roll mounted on one of said shafts, the other shaft being provided

adjacent one end portion with a fixed abutment and adjacent its other end portion with screw threads, a nut engaging said screw threads, and a sleeve and a roll on said last mentioned shaft, said roll being engaged with said abutment and 5 said sleeve being engaged with said nut, said roll having a conical bore and said sleeve having spaced extensions fitting into said bore, whereby said nut when tightened forces said extensions endwise of the roll to rigidly secure the latter to 10 said shaft.

3. In a machine of the class described, the combination with a pair of housings, of upper and lower shafts mounted therein, a roll mounted on one of said shafts, the other shaft being provided adjacent one end portion with a fixed abutment and adjacent its other end portion with screw threads, a nut engaging said screw threads, and a pair of elements interposed between and 15 respectively engaging said abutment and said nut, 20 one of said elements consisting of a sleeve engaging said nut at one end and slidably fitting said shaft, the opposite end portion of said sleeve comprising a plurality of spaced extensions and the other element consisting of a roll engaging 25 said abutment and having a conical bore into which said extensions fit, whereby said nut when tightened forces said extensions endwise of the roll to rigidly secure the latter to said shaft.

4. In a machine of the class described, the combination with a pair of housings, of upper and lower shafts mounted therein, a roll mounted on one of said shafts, the other shaft being provided adjacent one end portion with a fixed abutment and adjacent its other end portion with screw 30 threads, a nut engaging said screw threads, and a pair of elements interposed between and respectively engaging said abutment and said nut, 35 one of said elements consisting of a sleeve one end of which engages said nut, the opposite end portion of said sleeve comprising a plurality of spaced extensions having outer surfaces tapered toward their free ends, said sleeve slidably fitting said shaft, and the other element consisting of a roll engaging said abutment and having a conical bore into which said extensions fit, said nut when 40 tightened being arranged to force said extensions endwise of the roll to rigidly secure the latter to said shaft.

5. In a machine of the class described, the combination with a support, of a shaft mounted at its opposite ends in said support, one end portion of said shaft being provided with a fixed abutment and its other end portion being provided with screw threads, a roll having a conical bore and surrounding said shaft in engagement with said abutment, a sleeve slidably fitting said shaft, one end portion of said sleeve having an outer conical wall and formed with a plurality of spaced slits extending inwardly from its free end to form extensions fitting into the conical bore of said roll, and a nut engaging said screw threads and arranged to be tightened against the other end of said sleeve to wedge said extensions between said shaft and said roll to rigidly secure the latter to said shaft.

CARL M. YODER.
